CLAIM

The ornamental design for a mobile phone with animated graphical user interface, as shown and described.

DESCRIPTION

1. Mobile phone with animated graphical user interface
1.1 is a front view of a first image of a mobile phone with animated graphical user interface;

1.2 is a front view of a second image thereof showing a mobile phone display screen with animated graphical user interface.

The broken line showing of a mobile phone is for the purpose of illustrating environment and form no part of the claimed design.

The process or period which one image transitions to another image forms no part of the claimed design.

1 Claim, 2 Drawing Sheets
